CLAIM

The ornamental design for a pedestal for vacuum pumps, as shown and described.

DESCRIPTION

1. Pedestal for vacuum pumps
- 1.1 : Perspective
- 1.2 : Perspective
- 1.3 : Top
- 1.4 : Bottom
- 1.5 : Front
- 1.6 : Back
- 1.7 : Left
- 1.8 : Right

This product is pedestal for vacuum pumps; the parallel thin lines and radial thin lines in the representation represent contours only and do not illustrate ornamentation or decoration on the surfaces of the products, which form no part of the claimed designs.
